UNITED STATES PATENT OFFICE.

STEPHEN M. SPRAGENS, OF CINCINNATI, OHIO.

CALENDAR.

Application filed March 1, 1922. Serial No. 540,816.

To all whom it may concern:

Be it known that I, STEPHEN M. SPRAGENS, a citizen of the United States, and a resident of Cincinnati, in the county of Hamilton and State of Ohio, have invented certain new and useful Improvements in Calendars, of which the following is a full, clear, and exact description, reference being had to the accompanying drawings, forming part of this specification.

My invention relates to calendars, particularly of the type known as art calendars.

There is one form of art calendar in which, for a saving in bulk and economy in paper, there has grown up the practice of providing a monthly calendar on each face, and using each sheet twice, reversing it after the first use.

In calendars of this type there is the necessity of preserving the used sheets, so that they may be preserved until both sides have been employed. It is also desirable to provide some means for advertising the business or name of the donor, without interfering with the context of the calendar, and without marring the effect of the artistic pictures formed in connection with the register of days of the month.

The usual method of preserving the sheets has been to provide a pad and mount it with a cord secured to the upper edges of the pad in such a way that the sheets may be turned back after use.

My object is to do away with the pad idea entirely and leave the sheets separate, but to provide a mounting card having proper space for advertising and forming in addition a pocket for mounting with full exposure the outermost sheet of the pile arranged in said pocket.

In this way the tearing of the corners of the sheets in folding back is obviated, and the mounting card on which the pocket is formed has at its upper extension a space for advertising.

I accomplish my object and other incidental advantages to be pointed out by that certain construction and arrangement of parts to be hereinafter more specifically pointed out and claimed.

In the drawings,

Figure 1 is a face view of a calendar formed according to my invention.

Figure 2 is a central vertical section through the calendar on the line 2—2 of Figure 1.

As a substantially stiff backing for the device I provide a card of the desired size formed with a body 1, and an upper extension 2, of the width of the completed calendar, on which the donor's name or advertisement may appear.

The body of the card is formed with side flaps 3, 3, and a bottom flap 4, said bottom flap being of full width of the original card, and the card slit so as to free the lower ends of the side flaps.

The side flaps are folded inwardly in making up the device, and the bottom flap then folded up and pasted to the lower portions of the side flaps to form corners 5.

The outlying ends of the bottom flap are then folded around to the back of the card, as at 4^a, and pasted down, thereby firmly securing the side flaps in their folded condition, and forming the base of a pocket, of which the side flaps form the sides.

The pocket so formed is almost entirely open at the front, so as to fully expose the sheets or leaves of the calendar.

Across the tops of the side flaps a piece 6 of material in strip form and of the same material (preferably) as the body of the card, is laid over the face and is secured by paste to the said side flaps. This strip also is of sufficient length to pass behind the body of the card, where it is again pasted, as at 6^a.

The strip 6 is thus separated from the body of the card and forms the top of the pocket for the calendar leaves. This strip is the only portion of the calendar leaf mounting device which is not integral with the mounting card.

The leaves 7 of the calendar in the desired number are thrust down between the top strip and the side strips, until they come between the card and the bottom strip, and are thus held flat by the said side, bottom and top flaps. It is easy to remove a leaf and insert it behind the pile, or, if so printed, to reverse it at once, for the ensuing month.

An aperture 8 in the exposed portion of the card at the top serves as a means for hanging the calendar to a hook or the like. If the top of the card ended at the upper end of the pocket, it is obvious that its formation at this point could be exactly like that at the lower end. In such a case the upper extension 2 would have to be pasted to the card.

I am aware that it is known practice to insert a card in a pocket having an open side

to expose the card, and aside from the method of forming the pocket and the combination of the pocket with the card, I do not claim invention in the broad idea of the pocket. 5 I do not wish to be limited because of failure to describe obvious mechanical equivalents for the parts shown in the drawings, and in detail described, in my claims that follow.

Having thus described my invention, what 10 I claim as new and desire to secure by Letters Patent, is:—

A calendar comprising a card having integral side flaps and a bottom flap of the full width of the body of the card and the side 15 flaps and separated from the side flaps, and

an extension of the width of the body of the card forming an advertising printing space, and a strip for forming the top of the pocket, thereby serving as a top pocket flap, said side flaps folded in toward the body of 20 the card, and the bottom flap and top flap arranged across the card and secured to the side flaps at their upper and lower ends, thereby forming a pocket for receiving date 25 registering leaves of the calendar, said top flap and bottom flap folded also back of the card at their ends, and there united with the card, as and for the purpose described.

STEPHEN M. SPRAGENS.
